(57) **CLAIM**

The ornamental design for a hair curling iron, as shown and described.

DESCRIPTION

FIG. 1 is a perspective view from the back of a hair curling iron showing my new design;

FIG. 2 is a top plan view thereof;

FIG. 3 is a bottom plan view thereof;

FIG. 4 is a front elevational view thereof;

FIG. 5 is a back elevational view thereof; and,

FIG. 6 is a left side view of the hair curling iron, the right side view being a mirror image of the left side view.

The broken lines in FIGS. 1-3 and 6 are for illustrative purposes only and form no part of the claimed design.

1 Claim, 2 Drawing Sheets
